CLAIM

The ornamental design for a heart shaped ornament as shown and described.

DESCRIPTION

FIG. 1 is a front, left, bottom perspective view of a heart shaped ornament showing my new design;

FIG. 2 is a rear, right, top perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines show in the drawings illustrate portions of the heart shaped ornament and form no part of the claimed design.
